(74) Attorney, Agent, or Firm — True Shepherd, LLC;
Andrew Cheng(57) **CLAIM**

The ornamental design for a case for mobile telephone, as shown and described.

DESCRIPTION

FIG. 1 is a front, right and top perspective view of a case for mobile telephone, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 6 comprising a button.

The dashed broken lines in the drawing figures form no part of the claimed design and illustrate portions of the case for mobile telephone that form no part of the claimed design. The dot-dash broken lines in FIGS. 6 and 9 form no part of the claimed design and designate the portion of the claimed design that is shown on an enlarged scale in FIG. 9.
